CLAIM

The ornamental design for an information handling system monitor, as shown and described.

DESCRIPTION

FIG. 1 is a front perspective view of the information handling system monitor comprising the present invention; FIG. 2 is an enlarged perspective view of the speaker and surface thereof as indicated in FIG. 1;

FIG. 3 is a front view thereof;

FIG. 4 is an enlarged front view of the speaker and surface thereof as indicated in FIG. 3;

FIG. 5 is a rear view of the monitor;

FIG. 6 is a left side view thereof;

FIG. 7 is a right side view thereof;

FIG. 8 is a top view thereof;

FIG. 9 is a bottom view thereof;

FIG. 10 is a rear perspective view thereof;

FIG. 11 is a rear perspective view of the monitor thereof in a folded configuration;

FIG. 12 is an enlarged perspective view of the speaker and surface thereof as indicated in FIG. 11; and,

FIG. 13 is a side view of the monitor thereof in a folded configuration.

Broken lines shown in the drawings illustrate portions of the information handling system monitor, and form no part of the claimed design.
